(57) **CLAIM**

The ornamental design for an adult toy as shown and described.

DESCRIPTION

FIG. 1 is a perspective view of an adult toy showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 shown in FIG. 5. The dash-dash broken lines in the drawings depict portions of the adult toy that form no part of the claimed design. The dash-dot-dot lines represent boundaries between the area that requires protection and other area and form no part of the claimed design.

The dot-dash broken lines represent boundaries of the enlarged portions and form no part of the claimed design.
